UNITED STATES PATENT OFFICE.

MATTHEW T. SCOTT AND JAMES L. BRASFIELD, OF BLUE SPRINGS, MISSOURI,
ASSIGNORS OF ONE-THIRD TO WILLIAM G. GORE, OF SAME PLACE.

CAR-COUPING.

SPECIFICATION forming part of Letters Patent No. 475,707, dated May 24, 1892.

Application filed February 24, 1892, Serial No. 422,666. (No model.

To all whom it may concern:

Be it known that we, MATTHEW T. SCOTT and JAMES L. BRASFIELD, citizens of the United States, residing at Blue Springs, in the county 5 of Jackson and State of Missouri, have invented a new and useful Car-Coupling, of which the following is a specification.

The invention relates to improvements in car-couplings.

10 The object of the present invention is to provide a simple and inexpensive car-coupling, which will couple automatically, and which may be readily uncoupled from the top of a car without injury to the operator by 15 passing between the cars, and which may be readily raised to couple with the ordinary pin-and-link coupling.

The invention consists in the construction and novel combination and arrangement of 20 parts hereinafter fully described, illustrated in the accompanying drawings, and pointed out in the claims hereto appended.

In the drawings, Figure 1 is a perspective view of a car-coupling constructed in accordance with this invention. Fig. 2 is a horizontal sectional view. Fig. 3 is a plan view illustrating the coupler arranged to receive a pin and a link. Fig. 4 is a detail perspective of the pin-and-link attachment.

30 Like numerals of reference indicate like parts in all the figures of the drawings.

1 designates the draw-head, having a stationary jaw 2 arranged at one side and provided at its other side with a spring-jaw 3, and having a space between the jaws adapted 35 for the reception of the stationary jaw of a twin coupling. The stationary jaw is shouldered at its outer side and has its outer end beveled slightly on both faces, and it is adapted to be engaged by the spring-jaw 3 of a twin coupling. The spring-jaw 3 is shouldered on its inner face, and it is adapted to engage the stationary jaw of another coupling.

The cars are uncoupled by a vertical shaft 45 4, which is journaled in suitable bearings on a car 5. It is provided at its upper end with an ordinary hand-wheel 6, and it has its lower end connected to chains 7 and 8, which are connected, respectively, with the outer end of 50 the spring-jaw 3 and with a lever 9, arranged

in the groove 10 of the stationary jaw 2. The lever 9 is fulcrumed intermediate its ends. It is arranged longitudinally on the stationary jaw at the outer face thereof and its outer end extends beyond the shoulder of the stationary jaw, and when the inner end of the lever is drawn inward the outer end will carry the shoulder of a spring-jaw out of engagement with the shoulder of the stationary jaw and will fill the recess, and thereby prevent 60 a spring-jaw engaging the stationary jaw. The inner end of the lever is attached to a rod 12, which is connected to the chain 8, the chain 7 passes around the pulley 13 at one side of the car, and when the shaft is turned 65 to wind the chain around it the spring-jaw will be drawn away from the stationary one and the outer end of the lever will be thrown outward laterally. The pulley 13 is arranged in a suitable bracket 14 and enables the lateral 70 pull upon the spring-jaw to be more direct. The jaws may be held against coupling by a pawl 15 and a ratchet-wheel 16, arranged on the top of the car. The rod 12 is arranged in a transverse opening of the draw-head, and 75 the chain 7 is provided with a turn-buckle take-up 17 to increase or diminish the length of the chain 7 to equalize the chains, whereby the proper pull on the spring-jaw and the uncoupling-lever may be obtained.

80 When it is desired to couple the car 5 with a car having the ordinary pin-and-link coupling, a pin-and-link attachment 18 is fitted on the draw-head and is provided with the ordinary link-cavity 19 and a coupling-pin perforation 20. The pin-and-link attachment is provided with a longitudinal slot 21, which is adapted to receive the stationary jaw and which conforms to the configuration of the same, and its side 22 is recessed and shaped 85 to conform to the configuration of the inner face of the spring-jaw 3. A transversely-disposed plate 23 is secured on the upper face of the pin-and-link attachment, and this plate secures the attachment to the draw-head and 90 rests upon the latter to prevent the pin-and-link attachment dropping from the jaws.

95 It will be seen that the car-coupling is simple and comparatively inexpensive in construction, that it couples automatically, and 100

that it may be readily uncoupled from the top of a car. By means of this ready coupling and uncoupling trains may be made up in much less time than by the ordinary coupling.

5 What is claimed is—

1. In a car-coupling, the combination of a draw-head having a stationary jaw at one side, a spring-jaw arranged at the other side, a lever arranged on the stationary jaw, and means for moving the lever and the spring-jaw laterally, whereby cars may be uncoupled, substantially as described.
2. In a car-coupling, the combination of a draw-head having a stationary jaw at one side shouldered on its outer face and provided with a longitudinal groove, a lever arranged in the groove and fulcrumed on the stationary jaw, a spring-jaw arranged at the other side of the draw-head and shouldered on its inner face, a shaft, and chains connected with the

lever and the spring-jaw and attached to the shaft and adapted to be wound on the latter, substantially as described.

3. The combination, in a car-coupling, of a draw-head having a stationary jaw at one side, a spring-jaw arranged at the other side, and a pin-and-link attachment having a slot conforming to the configuration of the stationary jaw and having one side conforming to the configuration of the spring-jaw, substantially as described.

In testimony that we claim the foregoing as our own we have hereto affixed our signatures in the presence of two witnesses.

MATTHEW T. SCOTT.
JAMES L. BRASFIELD.
